(57) **CLAIM**

The ornamental design for a fluid delivery set with anti-free flow feature as shown and described.

DESCRIPTION

FIG. 1 is a perspective view of a fluid delivery set with anti-free flow feature showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof, in an alternative use position.

The broken lines shown in the figures depict portions of the fluid delivery set with anti-free flow feature that form no part of the claimed design. The separations depicted by the break lines in the figures indicate an indeterminate length. Any portion of the article between the break lines forms no part of the claimed design.
